(57) **CLAIM**

The ornamental design for a fender hook, as shown and described.

DESCRIPTION

FIG. 1 is a front perspective view of a fender hook showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a rear elevation view thereof;

FIG. 7 is a front elevation view thereof;

FIG. 8 is a rear perspective view shown in an environment of use; and,

FIG. 9 is a front rear perspective view shown in an environment of use.

The broken lines in FIGS. 1-9 depict environmental subject matter of a rope and forms no part of the claimed design.

1 Claim, 5 Drawing Sheets**FIG. 2****FIG. 3**
